(57) CLAIM

The ornamental design for a vessel, as shown and described.

DESCRIPTION

FIG. 1 is a perspective view of a vessel, illustrating our new design;

FIG. 2 is a front elevational view of the vessel of FIG. 1; FIG. 3 is a rear elevational view of the vessel of FIG. 1; FIG. 4 is a left elevational view of the vessel of FIG. 1; FIG. 5 is a right elevational view of the vessel of FIG. 1; and, FIG. 6 is a top plan view of the vessel of FIG. 1.

The broken lines illustrate portions of the vessel that form no part of the claim.

1 Claim, 6 Drawing Sheets
